UNITED STATES PATENT OFFICE.

FREDERICK E. HOPKINS, OF STERLING, NEW YORK.

EXTENSION CAR-STEP.

No. 876,186.

Specification of Letters Patent.

Patented Jan. 7, 1908.

Application filed October 15, 1907. Serial No. 397,549.

To all whom it may concern:

Be it known that I, FREDERICK E. HOPKINS, a citizen of the United States, residing at Sterling, in the county of Cayuga and State of New York, have invented a new and useful Extension Car-Step, of which the following is a specification.

The invention relates to improvements in extension car steps.

10 The object of the present invention is to improve the construction of extension car steps, and to provide a simple, inexpensive and efficient one of great strength and durability, adapted to be readily fixed to the 15 steps of a railway passenger car or coach, and capable of being easily lowered into position for use, and raised after use by a single movement of an operating lever.

With these and other objects in view, the 20 invention consists in the construction and novel combination of parts hereinafter fully described, illustrated in the accompanying drawing, and pointed out in the claims hereto appended; it being understood that various 25 changes in the form, proportion, size and minor details of construction, within the scope of the claims, may be resorted to without departing from the spirit or sacrificing any of the advantages of the invention.

30 In the drawing:—Figure 1 is a perspective view of an extension car step, constructed in accordance with this invention and shown applied to a car, the car step being lowered to form a continuation of the car steps. Fig. 2 35 is a front elevation of the same, the extension step being raised. Fig. 3 is a detail view of the extension step and the bottom portion of the slidable step carrying frame.

Like numerals of reference designate corresponding parts in all the figures of the drawing.

1 designates an extension car step, designed to be applied to a passenger car or coach and adapted to be arranged below and 45 in spaced relation to the lower car step 2, as illustrated in Fig. 1 of the drawing to form a continuation of the car steps and enable passengers to readily enter and leave the car. The car step, which, when not in use, is arranged 50 against the lower face of the bottom step 2, as illustrated in Fig. 2 of the drawing, is carried by a slidable frame, composed of inclined sides 3 and a transverse bottom connecting portion 4, receiving the extension step

1 and provided with a central substantially 55 U-shaped bend 5, extending forwardly and secured to the lower face of the extension step by means of a central fastening device 6. The transverse connecting portion is secured to the extension step at opposite sides of the 60 forwardly extending loop by means of fastening devices 7, as clearly shown in Fig. 3 of the drawing. These fastening devices may consist of staples, and any number may be employed to secure a rigid connection between 65 the extension step and the slidable frame.

The sides 8 of the car steps are provided with alined guides 9, receiving the inclined sides of the slidable frame and consisting of eyes and attaching portions, secured to the 70 sides 8 by suitable fastening devices. The sides of the slidable frame are adapted to move upwardly and downwardly in the alined eyes of the guides 9, and the downward movement of the frame is limited by collars 75 8^a, secured to the upper ends of the sides of the slidable frame and arranged to engage the upper guides. The outer side of the slidable frame is connected at its upper end by a link 10 with a short arm 11 of an operating lever 80 12, fulcrumed at its angle and secured to the rear edge of the platform of the car by means of a suitable pivot 13. The operating lever, which swings transversely of the car, extends to the top of the railing, and is provided 85 at its upper end with a grip or handle. The upper ends of the inner and outer sides of the slidable frame are provided with eyes 14, and the link 10 has a corresponding eye, which is linked into the eye 14 of the outer 90 side of the slidable frame. By providing the eye 14 at both the inner and outer sides of the slidable frame, the extension step may be mounted at both the right and left hand sides of a car. The upper end 15 of the link is 95 bent at an angle to form a pivot, which passes through an eye or opening 16 of the short arm of the operating lever. The pivot 15 is secured in the eye or opening 16 by means of a nut 17, or other suitable fastening device. 100

The lever is oscillated to raise and lower the extension step, and the latter is retained in its raised position by means of a suitable keeper 18, consisting of a horizontally disposed substantially U-shaped body portion, provided at one side with a vertical arm 19, which is equipped with an eye 20. The eye 20 is arranged on the railing of the platform,

and is adjustably secured on the same by means of a set screw 21. When the lever is at the limit of its inward movement, it is engaged with the keeper 18 and is held by the same against outward movement.

Having thus fully described my invention, what I claim as new and desire to secure by Letters Patent, is:—

1. The combination with car steps provided at opposite sides with guides, of an extension step located beneath the car step, a 10 slideable frame composed of sides movable upwardly and downwardly in the guides, and a transverse bottom connecting portion receiving the extension step and provided at a point 15 between its ends with an approximately U-shaped loop or bend extending forwardly to the front portion of the extension step, fastening devices for securing the loop or bend 20 and the side portions of the bottom of the slideable frame to the extension step, and op-

erating mechanism for raising and lowering the slideable frame.

2. The combination with a car, of an extension step arranged beneath the car steps, 25 a frame slideable on the car steps and extending beneath and supporting the extension step, a lever fulcrumed on the platform of the car and having a short arm, a link connecting the short arm with the outer side of the slideable frame, and a substantially U-shaped keeper arranged to be engaged by the lever, said keeper being provided with an arm having an eye adjustably secured to the railing of the car. 30

In testimony, that I claim the foregoing as my own, I have hereto affixed my signature in the presence of two witnesses.

FREDERICK E. HOPKINS.
